UNITED STATES PATENT OFFICE.

FRED W. GARVIN, OF JAMESTOWN, NEW YORK.

DUMP WAGON.

Application filed November 19, 1925. Serial No. 70,121.

This invention relates to an improvement in a dumping wagon, and more particularly to a wagon in which the body is pivotally mounted, so that it may assume three positions, acting in one position as a scraper to take on material, in another position to dump the material and in the third or intermediate position to carry the material from one point to another.

10 The primary object of this invention is to provide a dumping wagon of this type in which the body is normally in the carrying position, but can be shifted to either the scraping position or dumping position easily, being caused to assume such positions by the operation of a shaft actuated either manually or by the forward traction of the rear wheels.

20 Other objects of this invention will appear from a consideration of the following description taken in connection with the drawings, which form a part thereof, and in which

25 Fig. 1 is a plan view of a wagon embodying this invention with the body in the carrying position;

Fig. 2 is a perspective view showing the body in the scraping position;

30 Fig. 3 is a perspective view showing the body in the dumping position;

Fig. 4 is a side elevation showing the body in the carrying position;

Fig. 5 is a sectional view taken along the line 5—5 of Fig. 1; the gearing being taken 35 along the section lines 5^A—5^A;

Fig. 6 is a perspective view of the front of the body;

40 Figs. 7 and 8 are views of the details of construction; Fig. 7 being taken along the line 7—7 of Fig. 1;

Fig. 9 is a view of a wrench which can be used manually to operate the body when the wagon is stationary;

45 Fig. 10 is a sectional view along the line 10—10 of Fig. 1; and

Fig. 11 is a view showing another form of axle that might be used if desired.

This invention is shown as embodied in a four wheel wagon 10, but it is understood 50 that it could equally well be embodied in a wagon having only a single front wheel or in a trailer having no front wheels at all, the essential point being the mounting of the wagon body 11 on the frame so it can be shifted from the scraping position into the carrying position or from the carrying posi-

tion into the dumping position by the rotation of the supporting or rear wheels. The wagon frame comprises the side rails 12 and the cross rails 13, which may be of channel iron, as shown in the drawing.

The rear axle 14 is preferably rigidly secured to the body 11, as shown particularly in Fig. 5 and is pivotally supported by the side rails 12. The wheels 15 are mounted in any suitable manner to rotate freely upon the ends of the axle 14, so that under ordinary conditions the traction of the wagon will have no effect whatsoever upon the axle 14 or the position of the body 11. Rigidly 70 secured to the hub 16 of each wheel 15 is a sprocket 17 and mounted upon each side rail 12 is a stub shaft 18, which carries a sprocket 19 in alignment with the sprocket 17. A chain or other connecting means 20 75 is employed to transmit motion between the sprockets 17 and 19, as shown in the drawings particularly in Fig. 4. It will be noted that the sprocket 17 is much larger in diameter than the sprocket 19 for obvious 80 reasons.

Rigidly secured to the sprocket 19 and carried by the stub shaft 18 is a gear 21, which meshes with a gear 22 mounted to rotate freely on a cross shaft 23. A clutch connection of the gears 22 with the shaft 23 is provided so that the gears can either rotate said shaft or can rotate freely thereon. For purpose of illustration the drawings show one type of clutch connection. The hub 24 90 of the gear 22 is provided with a notch 25, adapted to receive a boss 26 on the shaft 23. A coil spring 27 on the shaft 23 between the gear 22 and a locking nut 28 normally acts to urge the gear 22 laterally inward so that 95 the boss 26 will enter the notch 25 in the hub 24, and any rotation of the wheels be transmitted to the shaft 23.

In order to counteract this spring tendency and to prevent this inward movement 100 of the gear 22 and keep the boss 26 out of the notch 25 a suitable shifter mechanism may be employed. This may consist of a plate 29 pivotally mounted at 30 on a side rail 12, and having three arms 31, 32, and 33. The arms 32 and 33 extend in opposite directions from the pivot 30, while the arm 31 projects at right angles from the arm 32. The arm 31, when the plate is shifted 105 on the pivotal connection 30, will bear against the inner face of the gear 22 and force it laterally against the action of the 110

spring 27, moving the notch 25 away from the boss 26. Secured to the arm 33 of the plate 29 is a rod 34 which extends to the front of the vehicle and is attached to a lever 35, rigidly secured to a cross rod 36 mounted to rotate in the side rails. By raising the lever 35 the plate 29 is shifted on the pivot 30 pressing the arm 31 against the gear 22. This operation will be obvious from a consideration of Figs. 1 and 2 of the drawing.

Only the set of gears on one side have been described, but it will be understood that the other set functions in the same manner, and the same reference characters have been applied to each in the drawing. The plan view in Fig. 1 illustrates this mechanism, but it will be noted that only one shifter plate 29 with its associated elements is shown. This is because that to show the omitted plate would interfere with the showing of the brake mechanism described hereinbelow. The form of the notches 25 is such that unless the bosses 26 are fully seated therein, the gears will tend to move laterally and automatically declutch themselves.

The cross rod 36 is provided at the end opposite the lever 35 with a fixed plate 37, to which a rod 38 similar to the rod 34 is attached. The rod 38 transmits the movement of the rod 36 to the other shifter plate 29, (see Fig. 3), so that both gears 22 will be thrown out simultaneously.

As a regulator or check upon the movement of the shaft 23 a brake 40 is provided. This brake comprises a strap 41, which passes over a drum 42 integral with the shaft 23 near one of the side rails 12. One end of the strap 41 is secured to the rear cross rail 13 and the other end is secured to one arm 43 of a right angle lever 44, pivoted to the inner face of the side rail 12. The other arm 45 of the lever extends below the side rail 12 and terminates in a flange 46, which passes across and below the rail 12.

Supported by and above the floorboard 47 on the frame is a bar 48, which terminates at one end in a pedal 49, and is pivoted at 50. A similar bar 51 is supported by and below the floor board 47 being pivoted there-to at 52. The end of the bar 48 opposite the pedal 49 is connected to one end of the bar 51 by a link 53. To the other end of the bar 51 is attached a rod 54 which connects the bar 51 to the flange 46 of the lever 44. By applying pressure upon the pedal 49 the strap 39 is tightened upon the drum 42 of the shaft 23 and regulates its movement.

The wagon body 11 consists of a main portion or box 60, which is rigidly fixed to the rear axle 14. The box 60 is made in the form of a scoop having a bottom 61, side walls 62 and upper rear wall 63. In place of a fixed front wall there is provided a front gate 64 having side flanges 65, which

are pivoted upon the side walls 62 of the box 60 at 66 and 67. Fixed at the inner corners of the side and rear walls are angle iron posts 68, which project above the walls and have holes 69 therein for a purpose to be described hereinbelow.

At the inner corners of the gate 64 are fixed angle iron posts 70 similar to the posts 68, and also provided with holes 71 therein. Horizontal bars 72 are fixed to the front 75 face of the gate 64, the ends of the bars extending outwardly beyond the flanges 65. Notched supports 73 are secured to the side rails 12 in such a position that when the body is in the carrying position with the front gate 64 closed, (see Fig. 4), the bars 72 rest upon the notches 74 in the supports 73 and hold the body in that position. Due to its weight and the location of the pivots 66 and 67 the gate 64 normally tends to close 85 the front of the box 60.

Mounted to slide in straps 75 on the front of the gate 64 is a plate 76, (see Fig. 6). The lower end of the plate 76 passes through the space between the gate 64 and the floorboard 90 47 and has an outwardly projecting flange 77, which extends across the space below the board and to the upper end is pivoted at 78, one end of a lever 79. The lever 79 is pivoted at 80 to the gate 64 and has a handle 95 81, which projects above the gate 64. Fixed to the flange 77 is a chain 82, which rests on the floorboard 47 and which is used to raise the plate 76 when desired, as will be set forth later.

When the plate 76 is lowered from the Fig. 6 position the flange 77 will strike the floorboard, should the gate swing on its pivot, so that when the plate is lowered, the gate can not be opened.

The box 60 also has a rear gate 83 which normally closes the space between the upper rear wall 63 and the back edge of the bottom 61. The gate 83 has right angle flanges 84 pivoted at 85' to the side walls 62. Rigidly secured to the upper edge of the gate 83 is a bar 85, the ends of which project beyond the sides of the gate for a purpose to be described below.

Adjustably fixed in pockets 86 on the side 115 walls 62 by screws 87 are angle brackets 88, which can be adjusted so that the upper arms 89 are at any desired distance above the pockets 86. The under face of the bottom 61, of the box 60, at the front edge is reinforced by a metal plate 90, the front edge 91 of which is preferably sharpened, as shown in Fig. 3.

The posts 68 are higher than the posts 70 and have two sets of holes 69 therein. The 125 shaft 23 is supported in brackets 92 and has an enlarged portion or drum 93 between the brackets 92. Rigidly secured to the center of the drum 93 and to the upper holes 69 in the bars 68 is a line or cable 94.

The gears 22 are under ordinary conditions declutched from the shaft 23, the lever 35 being held in that position by means of a chain 95 which is secured to the handle of the lever, and one of the bars 70, (see Fig. 4.)

Furthermore, by reason of the flat face 96 of the arm 31, the pressure of the gear when declutched will bear across the entire face of the arm 31, and consequently will exert no tendency to swing the plate 29 on its pivot 30. When so set the wagon is used in the usual manner, the body being in the carrying position shown in Fig. 4. Upon reaching the place where the wagon is to pick up material the chain 82 is pulled up, first raising the plate 76 and drawing the flange 77 through the space between the floorboard and the front gate and then swinging the gate 64 on its pivots 66, 67, until the bars 72 leave the notches 74 in the supports 73. This removes the support for the front end of the box 60, which swings downwardly about the axle 14 while the gate slides down on the floorboard 47 under the support 96 for the seat 97. The box will swing down until the arms 89 of the brackets 88 strike the side rails 12 or the blade 79 rests on the ground.

The gears 22 being declutched, the wagon is drawn forward to scoop up the material until the body is filled. The lever 35 is then depressed to swing the plate 29 and permit the gears 22 to clutch the axle 23, so that as the wagon goes forward the shaft 23 and its drum 93 are rotated, winding up the cable 94 on the drum and raising the body from the scraping position. As the body is raised the front gate 64 will swing back into its normal position, which will be reached when the body has been raised, sufficiently so that the bars 72 are above the notches 74 in the supports 73. If the chain 95 is not attached to the posts 70 the gears 22 are thrown out by raising the lever 35 and the body takes its normal carrying position.

When the body is in the scraping position the posts 70 are so located that the chain 95 can be secured in one of the holes 71, when the lever 35 is depressed. As the body rises the posts 70 also straighten up and when the front gate is closed the posts 70 have reached such a position that the lever 35 is raised and the clutch thrown out automatically when the wagon is in the carrying position.

When the unloading point has been reached the gears 22 are again thrown into clutch with the axle 23 by removing the chain 95 from the post 70 and depressing the lever 35, so that, as the wagon goes forward the cable 94 is wound on the drum 93 tilting the body backward on the axle 14. The cross bar 85 on the rear gate 83 strikes the side rails 12, so that the gate opens as the body is tilted and the load slides out. As the body continues to tilt back the cross bar 85 slides along the rails until it strikes the

arms 32 on the clutch plates 29 and swings the plates 29 on the pivots 30 to throw the gears 22 out of engagement. When this takes place the axle 23, of course, is free to turn and the cable 94 to unwind from the drum to lower the body, but this may be prevented by the use of the brake 40, which can be set by the pedal 49 to hold the drum 93 stationary. When the load has been dumped the brake 40 is released allowing the body to return to its normal carrying position and the operations described are repeated.

Should there be any necessity for shifting the position of the body when the wagon is stationary the ends 98 of the shaft 23 are made rectangular and a lever 99 having a rectangular hole therethrough is provided so that the axle 23 can be turned manually in the proper direction.

The wagon here illustrated is of the four wheel type intended to be drawn by a pair of horses. The floor-board 47 is braced from the front cross piece 13 by channel irons to which are secured the front axle 100 and the shafts 101. Since as pointed out above this forms no part of applicant's invention and is shown for purposes of illustration only, it will not be described in detail.

While certain embodiments of this invention have been shown and described, applicant is not limited thereto, since it is obvious that other embodiments can be made without departing from the spirit and scope of this invention as set forth in the following claims.

Having thus set forth my invention, what I claim as new and for which I desire protection by Letters Patent is:

1. A dump wagon comprising a frame, an axle, wheels on said axle a cross shaft, connections between said wheels and said shaft including releasable clutch mechanism, a body pivotally mounted on said frame adapted to assume a scraping position a carrying position and a dumping position, said body comprising a box, a front gate and a rear gate, said gates being pivotally secured to said box, and means on said gates which engage said frame when said body is swung into said scraping position and said dumping position to move the lower edge of said front gate in the first instance and the lower edge of said rear gate in the second instance away from said box, and means connecting said shaft with said body whereby, when said clutch mechanism is set to function, the forward movement of said wheels will raise said body from said scraping position to said carrying position and from said carrying position to said dumping position.

2. A dump wagon including a frame, a body pivotally mounted on said frame adapted to assume a scraping position, a carrying position and a dumping position,

means for moving said body, said body comprising a box, a front gate, and a rear gate, said gates being pivotally secured to said box, and means on both said gates whereby 5 as said body assumes the scraping position, the means on said front gate engage said frame and move the lower edge of said gate away from said box and, as said body assumes the dumping position, the means on 10 said rear gate engage said frame and move the lower edge of said gate away from said box.

3. A dumping wagon including a frame, a body pivotally mounted on said frame 15 adapted to assume a scraping and carrying position and means for moving said body, said body comprising a box, a front gate pivoted upon said box and a rear gate and

means on said front gate for engaging said frame, as said body assumes the scraping 20 position, and swinging the lower edge of said gate on its pivots away from said box.

4. A dump wagon including a frame, a body pivotally mounted on said frame adapted to assume a carrying and a dumping position and means for moving said body, said body comprising a box, a front gate and a rear gate pivoted upon said box and means on said rear gate for engaging said frame, as said body assumes the dumping position, 25 and swinging the lower edge of said gate on its pivots away from said box.

In testimony whereof I have affixed my signature.

FRED W. GARVIN.
